UNITED STATES PATENT OFFICE.

WILLIAM BENNETT LOEWENBERG AND CHARLES LYONS, OF WABASH, INDIANA; SAID LYONS ASSIGNOR TO SAID LOEWENBERG.

LIFE-SAVING SUIT.

1,151,369.

Specification of Letters Patent. Patented Aug. 24, 1915.

Application filed October 8, 1914. Serial No. 865,715.

To all whom it may concern:

Be it known that we, WILLIAM BENNETT LOEWENBERG and CHARLES LYONS, citizens of the United States, residing at Wabash, in 5 the county of Wabash and State of Indiana, have invented certain new and useful Improvements in Life-Saving Suits; and we do declare the following to be a full, clear, and exact description of the invention, such 10 as will enable others skilled in the art to which it appertains to make and use the same.

Our invention relates broadly to improvements in life saving suits and more particularly to face plates or masks, for use in connection therewith.

The main object of the invention is to provide a protecting mask for the use of persons employing certain forms of life saving suits, whereby they may be shielded from water and from the weather, thereby increasing the efficiency of devices of this general character.

In carrying out the above end, a further 25 object of the invention becomes to provide simple means for retaining the mask in position upon the face of the user.

Yet another object, is to provide means on the mask whereby its attachment to the 30 hood of the life saving suit may be facilitated.

With the above and minor objects in view, the invention resides in certain novel features of construction and combination herein 35 described, and claimed, and shown in the drawings wherein:

Figure 1 is a front elevation of a device constructed in accordance with the invention; Fig. 2 is a vertical section as seen on 40 the line 2—2 of Fig. 1; Fig. 3 is a front elevation of the mask and the parts carried thereby; and Fig. 4 is a detail section, on an enlarged scale, taken on the line 4—4 of Fig. 3.

45 In the accompanying drawings, a life saving suit 1 is shown, which may be of any suitable construction and which is provided with a buoyant belt 2, and with a hood 3 whose forward side is open and provided 50 with a continuous seam 4 in which a draw string 5 is located, the free ends 6 of said draw string depending through an opening in the lower portion of said seam. The suit 1 and the hood 3 may be formed of any suit-

able water and weather proof material, 55 preferably rather heavy duck or canvas, which is usually provided with rather heavy lining (not shown). The construction of the suit, proper, however, forms no part of the present invention and further description thereof, is therefore deemed unnecessary.

Secured within the opening in the front of the hood 3 is a mask 7 which is preferably formed of aluminum, and which is shaped 65 to fit the face of a user, said mask being here shown as provided with a pair of breathing openings 8, and with a pair of lenses 9, the former being positioned in an outwardly bulged nose on the mask, while the latter are 70 properly positioned to stand directly in advance of the eyes of the user, as will be readily understood. The rear edge portion of the mask 7 is provided with a pair of spaced continuous ribs 10 between which the seam 75 4 is drawn by the draw string 5, the free ends 6 of said string being then tied as indicated in Figs. 1 and 2. By this means, the mask is held in proper relation to the hood 3 and is secured thereto in water tight 80 contact.

For the purpose of more readily retaining the mask in proper position upon the face, said mask is provided with a curved head band or strip 11, which curves rearwardly and downwardly from the upper central portion of said mask, and with a pair of cheek bands 12 which curve downwardly and outwardly from the band 11 and which are preferably secured to the 85 lower end of the mask. When the parts are in operative position, the band 11 contacts with the upper and rear portions of the head of the wearer, while the bands 12 contact with the side portions of the 90 head and with the cheeks.

The above described construction, will effectively retain the mask in active position at all times, in which position, the wearer of the suit is effectively shielded against 100 water and against the weather.

Although the masks could be furnished independently of the suits, they are preferably secured thereto by a rivet 13, which passes through the upper part of the hood 105 and through the head band 12.

From the foregoing, it will be seen that extremely simple construction has been pro-

vided for carrying out the objects of the invention, yet that the efficiency of the device will not be impaired by such simplicity.

We claim:

- 5 1. The combination with a hood having an open front and a draw string surrounding the same, of a mask closing the open front of said hood, a pair of spaced ribs surrounding the rear edge of said mask and receiving therebetween the draw string of said hood, and a resilient head embracing member carried by the mask and disposed within the hood.
- 10 2. The combination with a hood having an open front and a draw string surrounding the same, of a rigid mask closing said open front, and a pair of spaced ribs surrounding the rear edge of the mask and receiving the draw string therebetween.
- 15 3. The combination with a hood having an open front and a draw string surrounding said front, of a mask closing the open front of the hood, a pair of spaced ribs sur-

rounding the rear edge of the mask and receiving therebetween the draw string, and a resilient head embracing frame secured to the mask and disposed within the hood.

4. The combination with a mask, and a hood secured to and disposed in rear thereof, of a resilient head embracing frame secured to the mask and disposed in the hood.

5. The combination with a mask and a hood secured to and disposed in rear thereof, of a rearwardly and downwardly curving resilient head engaging strip secured at its front end to the mask, and additional head embracing strips depending from opposite sides of the first named strip.

In testimony whereof we have hereunto set our hands in presence of two subscribing witnesses.

WILLIAM BENNETT LOEWENBERG.
CHARLES LYONS.
